UNITED STATES PATENT OFFICE.

JAMES E. CHAPMAN, OF AKRON, OHIO.

DESIGN FOR A DECORATIVE MOLDING.

SPECIFICATION forming part of Design No. 36,176, dated December 23, 1902.

Application filed October 2, 1902. Serial No. 125,719. Term of patent 7 years.

To all whom it may concern:

Be it known that I, JAMES E. CHAPMAN, a citizen of the United States, residing at Akron, in the county of Summit and State of Ohio, have invented a new, original, and ornamental Design for Decorative Molding; and I do declare the following to be a full, clear, and exact description of the invention, such as will enable others skilled in the art to which it appertains to make and use the same.

The invention relates to a new, original, and ornamental design for decorative molding; and it consists of the design shown in the accompanying drawings, in which—

Figure 1 is a front perspective view, and Fig. 2 is a rear perspective view.

The leading feature of the design comprises the body portion, the front and rear faces and

sides of which are formed of corrugations. The bulges of the corrugations of the front face alternate with the bulges of the corrugations of the rear face, and the bulges of the corrugations of one side alternate with the bulges of the corrugations of the opposite side.

What I claim is—

A new, original and ornamental design for decorative molding, as herein shown and described.

In testimony whereof I have hereunto set my hand in presence of two subscribing witnesses.

JAMES E. CHAPMAN.
